Primary Examiner — Lauren D McVey*Assistant Examiner* — Justin A Johnson(74) *Attorney, Agent, or Firm* — Jeenam Park(57) **CLAIM**

The ornamental design for an ambient light, as shown and described.

DESCRIPTION

FIG. 1 is a perspective view of an ambient light showing my new design;

FIG. 2 is a front view thereof;

FIG. 3 is a back view thereof;

FIG. 4 is a left side view thereof;

FIG. 5 is a right side view thereof;

FIG. 6 is a top plan view thereof; and,

FIG. 7 is a bottom plan view thereof.

The broken lines shown in the drawings illustrate portions of the ambient light that form no part of the claimed design.
